TOY BATHINETTE FOR A DOLL

Jesse D. Horowitz, New York, N.Y., assignor to De Luxe Reading Corporation, Elizabeth, N.J., a corporation of New Jersey

Filed Jan. 26, 1965, Ser. No. 83,582

Term of patent 3½ years

(Cl. D34—15)

FIG. 1

I claim:

The ornamental design for a toy bathinette for a doll, substantially as shown.
